Attorneys

UNITED STATES PATENT OFFICE.

GEORGE AZONE, OF PHILADELPHIA, PENNSYLVANIA.

SIPHON FLUSH BOX.

Application filed April 29, 1925. Serial No. 26,567.

To all whom it may concern:

Be it known that I, GEORGE AZONE, a citizen of the United States, residing in Philadelphia, county of Philadelphia, and State of Pennsylvania, have invented a new and useful Siphon Flush Box, of which the following is a specification.

My invention relates to new and useful improvements in siphon flush tanks for water closets and the like, wherein water from the reservoir or tank is discharged into the water closet through a siphon having a double free end, and means to force an auxiliary jet of water into one of said free ends of the siphon pipe, thereby inducing a siphon flow in both of the free ends.

My invention relates to a new and useful siphon flush box wherein the water in the reservoir may be discharged into the water closet rapidly with the aid of an auxiliary stream or jet of water set into action by any suitable valve, operated by any convenient push button or pull chain such as are used on the ordinary type of flush tanks, and whereby moreover the amount of water necessary to start the siphon is greatly reduced, thereby reducing also the time required to actuate the auxiliary valve.

With the above ends in view my invention consists of a water supply tank, a discharge siphon with the same in an upright position, having its drawing or gravity end passing through the bottom of said supply tank, the free end of said siphon having a somewhat narrower branch extending from it at an angle, a water supply pipe leading into said tank and having thereon a float operated supply valve of the usual construction, as well as a manually operable auxiliary valve, actuating means for said auxiliary valve, a nozzle juxtaposed to the open end of the inclined branch pipe of said siphon and in alignment therewith, and a pipe connection from said auxiliary valve to said nozzle.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

In the drawings, in which like reference characters represents like parts;

Figure 1 represents a vertical section of a water tank or reservoir, having mounted therein a siphon flushing system embodying my invention.

Figure 2 represents a vertical section of the nozzle and the inclined branch pipe of the free end of the siphon, on an enlarged scale.

Figure 3 represents a section on line 3—3 of Figure 1, showing the flush or auxiliary valve.

Figure 4 represents a section on line 4—4 of Figure 3.

Referring to the drawings, 1 designates a water reservoir of the usual construction, having the side walls 2 and 3, the bottom 4 and the lid 5. The water supply pipe 6 of the usual construction, passes through the bottom of the tank at 7 and has secured to it, the refill valve 8, controlled by the float 9, through the pivotally mounted arm 10 of the usual construction. The relief pipe 11, also of the usual construction, interconnects said valve 8 with the discharge or gravity end 12 of the siphon 13. The discharge end 12 passes through the bottom 4 of the tank 1 and is secured thereto in the usual manner as shown at 14. The siphon 13 extends upward and is bent back upon itself, at substantially an angle of 180 degrees, above the normal level of the water when the tank is filled. The free end 15 of the said siphon 13 then extends down a substantial distance into the water. In order to permit the proper positioning of the top of the bend 16, which is the high point of the siphon, with respect to the level 17 of the water, the bend 16, well as the free ends 15 and 19, of the siphon are connected to the upright discharge or gravity end 12 of the siphon, by means of the adjustable slide joint 18.

The free end 15 of the siphon 13 is provided with a branch pipe 19 of a smaller diameter than the main pipe 15 and at an acute angle thereto, as shown particularly in Figure 1. The purpose of the inclined branch pipe of the free end of the siphon, is to induce a flow of water within the main pipe 15 of the siphon. This is accomplished by means of the nozzle 20, on the end of the auxiliary water supply pipe 21 connected to the valve 22, which nozzle is in alignment with the end of the inclined branch pipe 19, and positioned from the open end thereof a

slight distance, so that the jet of water issuing from the nozzle will not only enter the branch 19, and flow upward therein into the siphon, but will also carry or draw in with it, an added amount of water surrounding the nozzle, which water will thereby rise above the bend 16, and continue down the gravity end 12 of the siphon thereby starting a flow of water not only from the branch 19 pipe 19, but from the main pipe 15 of the free end of the siphon as well.

The action of the nozzle 20 is best seen in Figure 2. Due to the construction of the end of the nozzle 20, the auxiliary jet of water is reduced in diameter, with a corresponding increase in the velocity of the water. This narrow jet of water of high velocity, enters the open end of the inclined branch pipe 19, but since it in itself is not sufficient to fill the pipe, it draws in with it a certain amount of added water from the tank, which surrounds the end of the pipe 19 and the nozzle 20, and imparts to said water as well, a certain velocity. Due to the relatively high velocity of the water within the pipe 19, the same raises the level of the water in the bend at 23, until such water flows over the bend into the gravity end 12 of the siphon. Having thus once started the action of the siphon, the auxiliary jet of water through the nozzle 20, is discontinued and the water siphons out through both the pipes 15 and 19, as will be seen from Figure 1.

The supply pipe 6, connected to the refill valve 8, also communicates with the auxiliary valve 22, shown in detail in Figures 3 and 4, which valve may be of any suitable construction, such as the spring pressed valve disc, as shown. The discharge end of said valve 22 may be connected through an adjustable sliding coupling 24, with a pipe 21 and the nozzle 20. The stem 25 of the valve 22, carrying the valve disc 26, extends out through the front wall of the tank, and

carries at the outer end thereof, a push button, through which it may be actuated. Thus when it is desired to flush the closet, the button is pressed thereby displacing the valve disc 24, from the valve seat 2, against the tension of the spring 28, as well as against the pressure of the water supply, thus causing the water to flow through the pipe 21 and through the nozzle 20.

It will now be apparent that I have devised a novel and useful siphon flush box, which embodies the features of advantage enumerated as desirable in the statement of the invention and the above description, and while I have, in the present instance, shown and described a preferred embodiment thereof of which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent is:—

1. In a flush tank, a siphon having a gravity limb, and an open ended limb with two branches at an acute angle to each other, a nozzle in proximity to and in operative alignment with the inclined branch of said free end of the siphon, and means to discharge a jet of water through said nozzle into said inclined branch. 70
2. In a flush tank, a siphon having a gravity limb, and an open ended limb with two branches at an acute angle to each other, a nozzle in proximity to and in operative alignment with the inclined branch of said free end of the siphon, means to discharge a jet of water through said nozzle into said inclined branch, and means to adjust the height of the siphon. 75 80 85

GEORGE AZONE.
